201,917

VARIABLE RATIO TRANSMISSION OR SIMILAR ARTICLE

Don Heyer, 1019 N. Raymond Ave., Fullerton, Calif.

Filed May 11, 1964, Ser. No. 79,907

Term of patent 14 years

(Cl. D55—1)

FIG. 1 is a front perspective view of a variable ratio transmission or similar article showing my new design;

FIG. 2 is a rear perspective view thereof;

FIG. 3 is a front perspective view thereof in an alternate position; and

FIG. 4 is a rear perspective view thereof as shown in FIG. 3.

I claim:

The ornamental design for a variable ratio transmission or similar article, as shown.
